Primary Examiner — Amber R Stiles(74) *Attorney, Agent, or Firm* — Nitin Kaushik(57) **CLAIM**

The ornamental design for an automatic juicer, as shown and described.

DESCRIPTION

FIG. 1 is a front perspective view of an automatic juicer, showing my new design;

FIG. 2 is a rear perspective view thereof;

FIG. 3 is a front perspective view of the automatic juicer in a state of use;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof; and,

FIG. 10 is an enlarged detail view of area 10 in FIG. 1.

The broken lines in the drawings illustrate the portions of the automatic juicer, which form no part of the claimed design. The dash-dot-dash broken lines encircling the enlarged views are for annotative purposes only and form no part of the claimed design.

1 Claim, 10 Drawing Sheets(56)
